UNITED STATES PATENT OFFICE.

FLORENCE C. BIGGERT, JR., OF CRAFTON, AND LANE JOHNSON, OF INGRAM, PENNSYLVANIA, ASSIGNORS TO UNITED ENGINEERING AND FOUNDRY COMPANY, OF PITTSBURGH, PENNSYLVANIA, A CORPORATION OF PENNSYLVANIA.

MANIPULATOR.

Application filed May 24, 1923. Serial No. 641,148.

To all whom it may concern:

Be it known that we, FLORENCE C. BIGGERT, Jr., and LANE JOHNSON, both citizens of the United States, residing, respectively, at Crafton and at Ingram, both in the county of Allegheny and State of Pennsylvania, have invented a new and useful Improvement in Manipulators, of which the following is a full, clear, and exact description.

10 The present invention relates broadly to the metal-working art, and more particularly to manipulators for rolling mills.

In a manipulator for rolling mills, it is desirable that the parts operative upon the ingots to shift it laterally and to turn it on its axis, it being shifted back and forth transversely of the roll table, be given a straight-line motion. It is also desirable that these parts be supported and operated by means 15 positioned outside the area beneath the roll table in order to avoid the injurious effects of heat, scale and dirt upon the manipulator mechanism, and particularly upon the bearing surfaces of the movable parts thereof.

20 On the other hand, it is important that the parts referred to be supported as low as practicable with respect to the level of the roll table in order to render them readily accessible and to provide as compact a structure as possible. Furthermore, it is advantageous to support the operating parts of the manipulator mechanism entirely independently of the roll table itself in order that the manipulator may be readily assembled 25 or disassembled without disturbing the roll table, and may be positioned at any desired location with respect to the latter.

By the present invention we have provided a manipulator embodying the above and 30 other desirable features.

In the accompanying drawings, there is shown, for purposes of illustration only, one embodiment of the present invention, it being understood that the drawings do not define the limits of the invention, as changes 35 may be made in the construction and operation therein disclosed without departing from the spirit of the invention or scope of our broader claims.

40 In the drawings,—

Figure 1 is a plan view of a manipulator constructed in accordance with my invention and of a roll table with which it is associated;

Figure 2 is an end elevation, partly in section, of the structure shown in Figure 1;

Figure 3 is a transverse vertical sectional view taken on the line III—III of Figure 1;

Figure 4 is a detail view of the yielding pivotal support for a finger-carrying lever; and

Figure 5 is a detail sectional view taken on the line V—V of Figure 2.

The reference numeral 2 designates a roll table of the usual construction. The manipulator may conveniently be formed in two sections A and B positioned at opposite sides of the roll table and spaced laterally therefrom. The section A may comprise a side guard 3 for engaging and shifting the ingots laterally on the table, said side guard being supported above the level of the feed rollers and at right angles thereto, said side guard, in the construction illustrated, being carried upon an end of a pair of parallel beams 4 extending at right angles thereto and slidably mounted upon horizontal rails 5. The beams 4 may be formed as hollow castings of channel form at their bases, thereby providing depending lateral flanges 6 for engagement with the edges of the rails 5. Plates 7 bolted to the lower edges of the flanges 6 engage the under faces of the rails 5 and thereby maintain the beams in engagement with said rails.

By reference to Figure 3, it will be seen that a groove 8 is provided between the engaging surfaces of each beam 4 and its rail support 5. The grooves 8 may be supplied with a suitable lubricant, and, by reason of the fact that the rails 5 are positioned laterally of the roll table and at some distance therefrom, the lubricant will not be objectionably affected by the heat from the roll table as portions of the rails are alternately covered and uncovered during operation of the manipulator.

The bearing surfaces of the rails 5 are in a horizontal plane which is approximately coincident with a plane tangent to the feed rollers at the upper side thereof, although in the construction shown, the plane of said bearing surfaces is actually slightly below said tangent plane. This arrangement of the bearing surfaces of the rails 5 enables the beams 4 to be located in the same horizontal plane, approximately, as the side guard 3, so that all parts of the manipulator

are positioned relatively low with respect to the level of the roll table, thereby producing a very compact construction all the parts of which are readily accessible.

5 Reciprocation of the beams 4 upon the rails 5 may be effected by any suitable means, such as fluid-pressure cylinders. Referring to Figure 1, it will be seen that the beams 4 are actuated by a pair of cooperating alined cylinders 9 having a common piston rod 10. A pair of links 11 is pivotally connected at one end to the piston rod 10 and at its opposite end to a rocker arm 12 carried by a rock-shaft 13. The rock-shaft 13 is operatively connected to the beams by rocker arms 14 carried by the rock-shaft and links 15 connecting said rocker arms to said beams.

The pair of beams 4 is connected at its 20 end remote from the roll table by a brace bar 16 extending transversely of the section A and parallel to the side guard 3. The brace 16 insures uniform movement of the beams 4 and consequently of the side 25 guard 3.

Cooperating with the side guard 3 is a series of manipulator fingers 17 for engaging and turning the ingots on their axes. The fingers 17 are U-shaped, and each finger 30 is integrally connected to one end of a lever 18 which may be of inverted channel form. As shown, the levers 18 are pivotally connected at the end remote from the roll table to blocks 19 mounted for a limited sliding 35 movement upon the brace 16. In Figure 4 we have illustrated in detail the manner in which a block 19 is mounted upon the brace bar. As shown therein, the block 19 is mounted for limited sliding movement between a shoulder 20 on the brace 16 and a shoulder 21 on a cover plate 22. A bolt 23 extends through the shoulder 20 and the block 19 and is surrounded by a coil spring 24 interposed between the block and the 40 shoulder 20, and normally maintaining the block pressed against the shoulder 21. This construction provides a yielding pivotal connection for the finger-carrying levers 18 at one side of the roll table, so that in case an ingot tends to jam during the turning thereof, the fingers are enabled to yield toward the side guard and allow the side guard to take the entire lateral thrust of the ingot without breaking of the fingers.

55 A rock-shaft 25 is supported in and extends transversely of the section A adjacent the end thereof nearest the roll table. The rock-shaft 25 is connected with each of the levers 18 by means of a rocker arm 26 carried by the rock-shaft and a link 27 connecting the rocker arm to the corresponding lever 18 intermediate the ends of the latter. The rock-shaft 25 is actuated and controlled by a pair of cooperating alined 60 fluid-pressure cylinders 28 and 29 having a

common piston rod 30. A pair of links 31 is pivotally connected at one end to the piston rod 30 and at its other end to a rocker arm 32 carried by the rock-shaft 25.

By reference to Figure 5, it will be seen that each finger 17 is formed with a T-head 33 where it joins its lever 18, said T-head co-operating with shoulders 34 at the lower end of a slot 35 in the side guard 3 to limit the downward movement of the finger. The T-heads 33 of all of the fingers are normally maintained in engagement with the cooperating shoulders 34 by the fluid-pressure cylinder 28, which maintains sufficient pressure upon its piston to counteract the tendency of the levers 18 to swing upwardly during their reciprocation transversely of the roll table. It will be apparent, by reference to Figure 2, that during such movement of the levers 18 the pivot points 36 of the links 27 with the levers tend to move in arcs of circles and thereby cause the levers to swing vertically about their points of pivotal connection with the brace bar 16, but owing to the pressure in the fluid-pressure cylinder 28 on the piston therein, the T-heads 33 are maintained in engagement with the shoulders 34 during the aforementioned reciprocating movements of the levers, the fluid-pressure cylinder 28 actuating the rock-shaft 25 during such movements to maintain the said engagement between said T-heads and shoulders.

The fluid-pressure cylinder 29 is more powerful than the cylinder 28 and is, therefore, enabled to overcome the latter for rocking the rock-shaft 25 in a direction to raise the fingers 17 for turning the ingots on their axes after said ingots have been shifted laterally on the roll table.

We have designated the parts of the manipulator section B by the same reference characters as the corresponding parts of the section A but with said reference characters primed. The section B may be similar in construction to the section A. It will be noted, however, that in the construction shown the fluid-pressure cylinders 9' and 28' and 29' are arranged slightly differently from the corresponding fluid-pressure cylinders of the section A. It will further be noted that the finger-carrying levers 18' are formed with a raised portion to clear the roll table driving mechanism, and that these levers are pivoted directly to the brace bar 16'. Of course it will be understood that these levers may, if desired, be pivotally mounted for yielding movement, but ordinarily it will only be necessary to pivot the levers at one side of the table for yielding movement.

An important advantage of the present invention arises from the provision of a manipulator all of the supporting and operating parts of which are positioned outside

the area beneath the roll table and relatively low with respect to the level of the latter, thereby producing a very compact construction.

5. A further advantage of the invention arises from the provision of a manipulator in which the parts for engaging and manipulating the ingots have a straight-line movement transversely of the roll table.

10. Another advantage of the invention arises from the provision of a manipulator all parts of which are supported entirely independently of the roll table itself.

15. Still another advantage of the invention arises from the provision of a yielding pivotal connection between the finger-carrying levers at one side of the roll table and the supporting means for the corresponding side guard, whereby danger of breaking of 20 the fingers is avoided.

25. A still further advantage of the invention arises from the provision of bearing surfaces for the supporting means, for the side guards which are positioned laterally of the roll table at a distance therefrom sufficient to permit said surfaces to be lubricated without the lubricant being objectionably affected by the heat from the roll table.

We claim:

30. 1. In a manipulator, in combination with ingot feeding means, means movable transversely of and above said feeding means for engaging the ingots and shifting the same laterally on said feeding means, supporting 35 means for said ingot engaging means supported wholly outside the area beneath said feeding means and at approximately the level of the latter and independently thereof and for straight-line movement, means for actuating said supporting means, and ingot turning means mounted for movement independently of said first mentioned means in one direction, substantially as described.

40. 2. In a manipulator, in combination with ingot feeding means, means movable transversely of and above said feeding means for engaging the ingots and shifting the same laterally on said feeding means, supporting 45 means for said ingot engaging means supported independently of and wholly outside the area beneath said feeding means and below the level of the latter and for straight-line movement, means for actuating said supporting means, and ingot turning means 50 mounted for movement independently of said first mentioned means in one direction, substantially as described.

55. 3. In a manipulator, in combination with ingot feeding means, means movable transversely of and above said feeding means for engaging the ingots and shifting the same laterally on said feeding means, supporting 60 means for said ingot engaging means supported independently of and wholly outside the area beneath said feeding means and at

approximately the level of the latter and for straight-line movement, means for actuating said supporting means, ingot turning means connected to said supporting means for movement therewith, and means for 70 moving said ingot turning means vertically, substantially as described.

4. In a manipulator, in combination with ingot feeding means, means movable transversely of and above said feeding means for 75 engaging the ingots and shifting the same laterally on said feeding means, supporting means for said ingot engaging means supported independently of and wholly outside the area beneath said feeding means and at 80 approximately the level of the latter and for straight-line movement, means for actuating said supporting means, ingot turning means connected to said supporting means for movement therewith, means for causing said 85 ingot turning means to move with said supporting means in a straight line, and means for moving said ingot turning means vertically, substantially as described.

5. In a manipulator, in combination with ingot feeding means, means movable transversely of and above said feeding means for engaging the ingots and shifting the same laterally on said feeding means, supporting 90 means for said ingot engaging means supported wholly outside the area beneath said feeding means and at approximately the level of the latter and for straight-line movement, means for actuating said supporting 95 means, ingot turning means, means yielding connecting said ingot turning means to said supporting means for movement therewith, and means for moving said ingot turning means vertically, substantially as described. 100

6. In a manipulator in combination with ingot feeding means, means movable transversely of and above said feeding means for engaging the ingots and shifting the same laterally on said feeding means, supporting 105 means for said ingot engaging means slidably supported independently of and wholly outside the area beneath said feeding means and at approximately the level of the latter and for straight-line movement, and means for actuating said supporting means, substantially as described. 110

7. In a manipulator, in combination with ingot feeding means, a side guard movable transversely of and above said feeding means for engaging the ingots and shifting the same laterally on said feeding means, rails having their supporting surfaces arranged wholly outside the area beneath the feeding means and below the level of the latter, beams supporting said side guard and slidably supported upon said rails, and means for reciprocating said beams on said rails, substantially as described. 115

8. In a manipulator, in combination with 120

ingot feeding means, a side guard movable transversely of and above said feeding means for engaging the ingots and shifting the same laterally on said feeding means, 5 rails having their supporting surfaces arranged wholly outside the area beneath the feeding means and below the level of the latter, beams supporting said side guard and slidably supported upon said rails, 10 means for reciprocating said beams on said rails, fingers for engaging and turning the ingots, levers supporting said fingers at one end thereof and pivotally connected at the other end thereof to said beams whereby to 15 cause said levers to move with said beams, and means for moving said levers about their pivots to shift said fingers in a vertical direction, substantially as described.

9. In a manipulator, in combination with 20 ingot feeding means, a side guard movable transversely of and above said feeding means for engaging the ingots and shifting the same laterally on said feeding means, rails having their supporting surfaces arranged 25 wholly outside the area beneath the feeding means and below the level of the latter, beams supporting said side guard and slidably supported upon said rails, means for reciprocating said beams on said rails, 30 fingers for engaging and turning the ingots, levers supporting said fingers at one end thereof and pivotally connected at the other end thereof to said beams whereby to cause 35 said levers to move with said beams, means for moving said levers about their pivots to shift said fingers in a vertical direction, means for limiting downward movement of said fingers, and means for maintaining said fingers at the limit of their downward 40 movement during the movement thereof with said beams, substantially as described.

10. In a manipulator, in combination with 45 ingot feeding means, means affording a sliding supporting surface wholly at one side of said feeding means and below the level of the latter, supporting means slidably sup-

ported upon said surface, said supporting means and said surface having a lubricant holding recess therebetween, means carried by said supporting means for engaging and shifting the ingots on said feeding means, and means for reciprocating said supporting means on said supporting surface, substantially as described.

11. In a manipulator, in combination with 50 ingot feeding means, means for shifting the ingots laterally on said feeding means, supporting means for said shifting means slidably supported wholly outside the area beneath said feeding means and below the 55 level of the latter, ingot turning means, a lever supporting said ingot turning means at one end thereof, a member having a limited sliding movement on said supporting means and having said lever pivoted at 60 its other end thereto, yielding means for normally maintaining said member at one limit of its sliding movement, and means for swinging said lever about its pivot to raise and lower said ingot turning means, 65 substantially as described.

12. In a manipulator, in combination with 70 ingot feeding means, ingot shifting means, means affording a plurality of bearing surfaces wholly at one side of said feeding 75 means and below the level thereof, supporting means for said ingot shifting means slidably supported upon said surfaces, a rock-shaft, means connecting said rock-shaft with said supporting means, means for actuating said rock-shaft, a plurality of ingot turning members, levers supporting said 80 ingot turning members and pivoted to said supporting means, a second rock-shaft, means connecting said second rock-shaft to 85 said levers, and means for actuating said second rock-shaft, substantially as described.

In testimony whereof we have hereunto set our hands.

FLORENCE C. BIGGERT, JR.
LANE JOHNSON.
